UNITED STATES PATENT OFFICE.

CHARLES NUHRING, OF CINCINNATI, OHIO.

PUMP FIRE EXTINGUISHER.

Application filed October 18, 1921. Serial No. 503,493.

To all whom it may concern:

Be it known that I, CHARLES NUHRING, a citizen of the United States, residing at Cincinnati, in the county of Hamilton and State 5 of Ohio, have invented certain new and useful Improvements in Pump Fire Extinguishers, of which the following is a specification.

The present invention relates to improvements in chemical fire-extinguishers of the portable type.

The object of the invention is to improve the construction of portable extinguishers to render them more effective in operation by 10 including therein a pumping device for the discharge of the chemical extinguishing agent. The inclusion of such pumping element enables expulsion of the agent under positive impulses of the pump, as distinguished from the pressure created by a gas generated by the commingling of an acid and an alkaline solution, thereby assuring at all times the proper discharge of the extinguishing agent when required for use and 15 maintaining uniform pressure on the agent throughout the entire operation of emptying the tank. This obviously is advantageous over the pressure of a gas which gradually diminishes, and insures to the user adequate 20 discharge of the extinguishing agent to the limit of the contents thereof within the tank.

A further object of the invention is to provide a pump fire-extinguisher of the general class referred to wherein is embodied 25 convenient and simple means for preventing the pump becoming air-bound in its operation of discharging the tank, and likewise for precluding deterioration of the chemical extinguishing agent within the tank either 30 by evaporation or by absorption of moisture 35 from the atmosphere. The strength of the agent, therefore, is preserved.

Furthermore, the invention also contemplates such an organization and correlation 40 of the parts of the extinguisher as to render the latter compact, easily accessible for operation when such is required, and readily replaced in event of impairment of the extinguisher.

With these general objects in view, and others which will appear as the nature of the improvements is better understood, the invention consists substantially in the novel construction, combination and arrangement 45 of parts hereinafter fully described, illus-

trated in the accompanying drawings, and finally pointed out in the appended claims.

As disclosed herein, the invention is delineated in one of its practical forms, but this disclosure is to be taken only in an 60 illustrative rather than a restrictive sense.

In the drawings—

Fig. 1 is a vertical transverse sectional view of a fire-extinguisher constructed in accordance with the present invention; 65

Fig. 2 is a top plan view thereof;

Fig. 3 is an inverted plan view of the extinguisher;

Fig. 4 is a fragmentary transverse sectional view of the base of the tank taken at 70 right angles to the line of section of Fig. 1;

Fig. 5 is a detail sectional view on the line 5—5 of Fig. 1 certain parts being omitted.

Referring in detail to the accompanying drawings, the numeral 10 designates the 75 tank of the herein-described extinguisher. This is formed preferably of copper, as is usual with chemical fire-extinguishers. The top of the tank is exteriorly screw threaded, and engaging said threaded end is a 80 cap 11 having a depending flange which is interiorly screw threaded for cooperation with the threads of the tank. The cap 11 also preferably is provided with a ring 12 which constitutes a handle for the convenient manipulation of the extinguisher. 85

At the central portion of the cap 11 is formed an opening about which, at the inner side of the cap, is a depending annular flange 13, said flange being integral with 90 the cap, and arranged within said flange 13, and suspended from the cap 11, is the elongated barrel 14 of a pump, which barrel has its lower end screw threaded and to which is connected the nipple 15 of a valve cage screen 16. The upper end of the nipple 15 constitutes a valve seat, and cooperating therewith is a vertically movable valve 17 which rests upon said seat and controls communication between the lower end of the barrel 14 and the interior of the tank 10. The valve 17 has a stem 18 extending downwardly therefrom and to which is connected a head 19 by which the upward movement of the valve 17 is limited. 100

A piston rod 20 is also arranged within the barrel 14, the upper end of said rod extending through the central opening of the cap 11 and projecting above said cap, and arranged at the lower end of said rod 20 is 110

a valve cage 21 having a series of lateral ports 22, a ball valve 23 being located within said cage 21. The valve 23 controls the passage 24 which extends through a piston 25 connected at the lower end of the cage 21. Thus it will be seen that the valve 17 will be drawn upwardly on the upstroke of the piston rod 20, while the valve 23 seats on such upstroke, the downstroke of the rod 20 causing the valve 17 to seat, while the valve 23 becomes unseated and establishes communication between the passage 24 of the piston 25 and the space within the barrel 14 above said piston.

15 The head of the barrel 14 is tapped by a discharge pipe 26, the inner end of which pipe is detachably connected to the head of the barrel 14, as by a suitable screw threaded connection, said pipe 26 extending through 20 a packing gland 27 formed in the wall of the tank 10, and thereby providing a properly fitted joint between the discharge pipe 26 and the tank 10. A hose 26^a is connected to the outer end of the discharge pipe 26 25 for directing the extinguishing agent as it is discharged from the tank.

At a suitable point in the cap 11 is formed a filling opening in which is fitted a closure plug 28, and at opposite points with respect 30 to the central opening of said cap is also provided a pair of vent openings 29. The purpose of these openings is to admit air to the tank 10 under proper conditions of use, and thereby to prevent the pump within 35 the tank becoming air bound. At the exterior of the piston rod 20, and disposed above the cap 11, is a head 30 having oppositely disposed handles 31 at its upper portion, while at its lower portion is formed a 40 pair of oppositely disposed locking arms 32. These arms, when positioned over the vents 29, serve to close said vents and prevent admission of air to the interior of the tank 10. This precludes deterioration of the 45 chemical extinguisher within the tank either by absorption of moisture from the atmosphere or by evaporation. The locking arms 32 cooperate with a pair of oppositely-disposed reversely-arranged locking lugs 33, 50 each of which locking lugs 33 has an overhanging flange under which the outer extremity of one of the locking arms 32 is adapted to fit. The under surface of the flanges of the lugs 33 is wedge shaped, and 55 by reason of the reverse arrangement of said lugs with respect to each other it will be apparent that as the locking arms 32 pass beneath said flanges the wedge shape of the latter will force the locking arms into tight 60 engagement with the cap 11, and thus effectually close the vents 29. This wedging action has the further function of forcing the piston 25 into engagement with the upper end of the valve 17, which action 65 serves to lock said valve upon its seat, and

thereby prevent displacement of said valve 17 from the latter.

To anchor the extinguisher during the operation of the pump one side of the base thereof is provided with an opening 34, and 70 extending across the lower end of the base, in proximity to said opening 34, is a web 35 which constitutes a rest for the foot of the operator which is introduced to the opening 34. This construction enables the application 75 of the foot to the web 35 in order to hold the extinguisher in position during the pumping operation.

In the operation of the herein described extinguisher the same is filled by the removal 80 of the closure plug 28, at which time the desired chemical extinguishing agent may be introduced to the interior of the tank 10. With the plug 28 fitted to its opening 85 in the cap 11 and the piston rod 20 moved to the limit of its inward motion, the piston 25 will contact with the valve 17. Rotation now exerted upon the piston rod 20 will draw the locking arms 32 into engagement 90 with the flanged locking lugs 33, which movement positions said locking arms over the vents 29, sealing the interior of the tank 10 from communication with the atmosphere, during which rotation of the rod 20 the piston 25 will also bind the valve 17 to its seat. When the extinguisher is required 95 for use, it is but necessary to rotate the piston rod 20 to release the locking arms 32 from engagement with the lugs 33, and in this movement the valve 17 is rotated 100 upon its seat so that in the event of corrosion, which may possibly arise by reason of the chemical extinguishing agent within the tank 10, the valve 17 will be freed and rendered capable of proper movement in the 105 action of the pump. Reciprocatory movement now being imparted to the rod 20 the extinguishing agent will be drawn from the tank 10 into the pump barrel 14 and discharged therefrom through the pipe 26 and 110 the hose 26^a to the point of service. The pumping action continues until the tank 10 has been depleted of the extinguishing agent, whereupon said tank may be filled 115 again, in the manner indicated, and is thus charged for further use.

In the event the separation of the parts is required, it is simply necessary to free 120 the locking arms 32 from engagement with the lugs 33, detach the head 30 from the rod 20, and disconnect the discharge pipe 26 from the head of the pump barrel 14. The parts then may be wholly removed from the tank 10 and readily separated.

I claim:

1. In a fire-extinguisher of the class described, the combination with a tank, of a cap therefor provided with a plurality of vent openings leading into the top of the tank, a pumping attachment associated with 125

said cap and arranged within said tank, means associated with said pumping attachment for closing said vent openings, locking means cooperating with said closing means to hold the latter in closed relation to said vent openings, and a discharge pipe connected to said pumping attachment.

2. In a fire-extinguisher of the class described, the combination with a tank, of a cap therefor provided with a plurality of vent openings, a pumping attachment associated with said cap and arranged within said tank, means associated with said pumping attachment for closing said openings, locking means for holding said closing means in closed relation to said vent openings, a valve included in said pumping attachment for controlling communication between the latter and the interior of said tank, and means for locking said valve upon its seat simultaneously with the locking of the closing means for controlling said vent openings.

3. In a fire-extinguisher of the class described, the combination with a tank, of a cap therefor having a vent therein leading into the top of the tank, a pumping attachment associated with said cap, means for actuating said pumping attachment, means associated with said actuating means for closing said vent, means for locking said closing means in position over said vent, and a discharge pipe connected to said pumping attachment.

4. In a fire-extinguisher of the class described, the combination with a tank, of a cap therefor having a vent therein, leading into the top of the tank, a pumping attachment suspended from said cap within said tank, means at the exterior of said cap for actuating said pumping attachment, means also arranged at the exterior of said cap and associated with said actuating means for closing said vent, means for locking said closing means in position over said vent, and a discharge pipe connected to said pumping attachment.

5. In a fire-extinguisher of the class described, the combination with a tank, of a cap therefor having a vent therein leading into the top of the tank, a pumping attachment associated with said cap, means for actuating said pumping attachment, means associated with said actuating means for closing said vent, a locking lug carried by said cap and with which said closing means cooperate for locking the closing means in position over said vent, and a discharge pipe connected to said pumping attachment.

6. In a fire-extinguisher of the class described, the combination with a tank, of a cap therefor having a vent therein, leading into the top of the tank, a pump barrel suspended from said cap within the tank, a

a piston rod connected to said piston and extending through said cap, means associated with said piston rod for closing said vent, means for locking said closing means in position over said vent, and a discharge pipe connected to said pump barrel.

7. In a fire-extinguisher of the class described, the combination with a tank, of a cap therefor having a vent therein, leading into the top of the tank, a pump barrel suspended from said cap within said tank, a controlling valve arranged at the lower end of said pump barrel, a piston rod connected to said piston and projecting through said cap, means associated with said piston rod for closing said vent, means for locking said closing means in position over said vent, said piston rod when said closing means are locked in position to close the vent serving also to lock the controlling valve of the pump barrel in engagement with its seat, and a discharge pipe connected to said pump barrel.

8. In a fire-extinguisher of the class described, the combination with a tank, of a cap therefor having a vent therein, a pumping attachment associated with said cap, means for actuating said pumping attachment, a locking arm associated with said pumping attachment for closing said vent, a locking lug carried by said cap for holding said locking arm in closed position over said vent, and a discharge pipe connected to said pumping attachment.

9. In a fire-extinguisher of the class described, the combination with a tank, of a cap therefor having a plurality of vents therein leading into the top of the tank, a pumping attachment associated with said cap and suspended thereby within said tank, means for actuating with pumping attachment, locking arms associated with said actuating means for closing said vents, a plurality of locking lugs carried by said cap and with which said locking arms cooperate for holding the locking arms in closed position over said vents, and a discharge pipe connected to said pumping attachment.

10. In a fire-extinguisher of the class described, the combination with a tank, of a cap therefor having a plurality of vents therein leading into the top of the tank, a pump barrel depending from said cap, a valved piston arranged within said pump barrel, a piston rod connected to said piston and passing through said cap, a valve seat arranged at the lower end of said barrel, a valve associated with said seat and controlling communication between the interior of the tank and the interior of said barrel, oppositely disposed locking arms carried by said piston rod at the exterior of said cap and serving to close said vents, and a plurality of oppositely disposed overhanging lock-

- ing lugs carried by said cap and with which said locking arms are adapted to engage to hold the locking arms in closed position over said vents, the engaging faces of the locking arms and the locking lugs being beveled to exert a wedging action when said arms are brought into engagement with said lugs, whereby to maintain the locking arms over the vents of the cap and also to engage said piston with the valve controlling communication between the tank and the pump barrel and thereby lock said valve upon its seat concurrently with the locking of said arms over said vents.
11. In a fire-extinguisher of the class described, the combination with a tank, of a cap therefor having a plurality of vents therein leading into the top of the tank, a pump barrel depending from said cap and provided at its lower end with a valve seat, a valve co-operating with said seat to control communication between the interior of the tank and the pump barrel, a valved piston mounted for movement within said barrel, a piston rod connected to said piston and extending through said cap, a handle de-

tachably connected to said piston rod and provided with oppositely disposed locking arms adapted to co-operate with the vents of the cap to close said vents, oppositely disposed clamping lugs also carried by the cap and with which said locking arms co-operate, the engaging faces of said locking arms and said locking lugs being beveled to exert wedging action when said locking arms are brought into engagement with said lugs, whereby to clamp the locking arms into engagement with said cap and simultaneously exert pressure upon the valve of the pump barrel to hold the latter to its seat and prevent communication between the tank and the pump barrel, and a discharge pipe connected to said pump barrel and extending to the exterior of the tank.

In testimony whereof I have hereunto signed my name in the presence of two subscribing witnesses.

Certificate of Correction.

It is hereby certified that in Letters Patent No. 1,486,600, granted March 11, 1924, upon the application of Charles Nuhring, of Cincinnati, Ohio, for an improvement in "Pump Fire Extinguishers," an error appears in the printed specification requiring correction as follows: Page 3, line 91, claim 8, after the word "therein" insert the phrase and comma *leading into the top of the tank,;* and that the said Letters Patent should be read with this correction therein that the same may conform to the record of the case in the Patent Office.

Signed and sealed this 6th day of May, A. D. 1924.

[SEAL.]

KARL FENNING,
Acting Commissioner of Patents.
